CLAIM

The ornamental design for a tire tread, as shown and described.

DESCRIPTION

FIG. 1 is a perspective view of a full tire including the tire tread of the present application;

FIG. 2 is a side view of a first side (inside) thereof;

FIG. 3 is a side view of a second side (outside) thereof;

FIG. 4 is a front view thereof; and,

FIG. 5 is an enlarged, partial front view thereof.

The broken line showings of the sidewall from the inner bead to the tire tread are included for the purpose of illustrating environment and form no part of the claimed tire tread. The tread pattern is understood to repeat throughout the circumference of the tire.

1 Claim, 5 Drawing Sheets
